UNITED STATES PATENT OFFICE.

DAVID E. HUNTER, OF CAMBRIDGE, MASSACHUSETTS.

DESIGN FOR A BEAM.

SPECIFICATION forming part of **Design No. 25,034, dated December 31, 1895**

Application filed August 7, 1895. Serial No. 558,555. Term of patent 14 years.

To all whom it may concern:

Be it known that I, DAVID E. HUNTER, a citizen of the United States, residing at Cambridge, in the county of Middlesex and Commonwealth of Massachusetts, have invented and produced a new and original Design for a Beam, of which the following is a specification, reference being had to the accompanying drawing, showing the same.

o The drawing is a perspective view of a beam, showing my design.

Referring to the drawing, looking at the end or a cross-section of the beam, my design consists in the **U**-shaped middle portion *a*, with the rolls or curves *b* at the two ends of the **U**, as shown.

The leading feature of my design is the beam having a **U**-shaped middle with its ends rolled back at the outside of the **U**.

I claim—

The design for a beam as herein shown and described.

In testimony whereof I have signed my name to this specification in the presence of two subscribing witnesses.

DAVID E. HUNTER.

Witnesses:

JOHN C. EDWARDS,
AUGUSTA E. DEAN.
